UNITED STATES PATENT OFFICE

151,599

DESIGN FOR A TOY RATTLE OR SIMILAR ARTICLE

Jack Colm, New York, N. Y.

Application July 14, 1948, Serial No. 147,562

Term of patent 7 years

(Cl. D34—15)

To all whom it may concern:

Be it known that I, Jack Colm, a citizen of the United States of America, residing in New York, county of New York, and State of New York, have invented a new, original, and ornamental Design for a Toy Rattle or Similar Article, of which the following is a specification, reference being had to the accompanying drawing, forming part thereof.

Fig. 1 is a front view of a toy rattle or similar article, showing my new design.

Fig. 2 is a side view thereof.

I claim:

The ornamental design for a toy rattle or similar article, substantially as shown.

JACK COLM.
